Attorney, Agent, or Firm—Bradford R. L. Price; Paul C. Flattery[57] **CLAIM**

The ornamental design for a portable hemapheresis device, as shown and described.

DESCRIPTION

FIG. 1 is a perspective view of a portable hemapheresis device in accordance with the invention with the cover in the closed position;

FIG. 2 is a perspective view of the device shown in FIG. 1 with the cover in the open position;

FIG. 3 is a front elevational view of the device shown in FIG. 2;

FIG. 4 is a side elevational view of the device shown in FIG. 2 viewed from the right;

FIG. 5 is a side elevational view of the device shown in FIG. 2 viewed from the left;

FIG. 6 is a top plan view of the device shown in FIG. 2;

FIG. 7 is a rear elevational view of the device shown in FIG. 2; and,

FIG. 8 is a bottom view of the device shown in FIG. 2.
